MAXIMILIAN ALMA AND CARL EGON ALMA, OF VIENNA, AUSTRIA.

DRAW AND BUFFER GEAR FOR RAILWAY VEHICLES AND THE LIKE.

Application filed November 3, 1925, Serial No. 66,581, and in Austria August 1, 1925.

The invention has reference to an improvement of the draw and buffer gear for railway vehicles of the kind extending from one car end to the other and comprising 5 two sections that are longitudinally displaceable and are connected to each other by a central portion, so that both sections can move in a certain degree to and from each other; the construction being so as to 10 permit the said sections of abutting upon movement towards each other. According to this invention not only springs are provided that act on the underframe upon tractive efforts or buffing thrusts, but also 15 springs that act from either section of the draw and buffer gear on the other.

The improvement consists in the following arrangement:

20 A special connection between both sections is provided so as to cause also tractive efforts—just as impact forces—to be transmitted from either part of draw-bar to the other under the action of the same springs as upon shocks.

25 The springs acting from one section on the other may be provided only on one end of the central connecting member. The other end of this member may be firmly connected to the draw-bar half extending into this end of the connecting member. The middle connecting member in this case takes part in the motions of one draw-bar half, whilst it is movable relatively to the other half, just as is that draw-bar half to 30 which it is firmly connected; thereby springs are dispensed with without an appreciable change in operation.

Also this mode of construction enables 40 all drawing and buffing stresses exceeding a certain amount which result from the compression of springs to be transmitted centrally by means of the middle connecting member situated in the longitudinal axis of the car, or directly by the draw-bar halves, abutting in the longitudinal axis of 45 the car.

Moreover the construction is such, that by 50 means of the springs situated near the central connecting member—the said springs are not supported against any parts of the underframe but are bodily slideable together with the draft gear—upon the occurrence of a tractive or buffing effect at either car end also the opposite draw-bar half is moved 55 into or out of the car to a certain degree dependent upon the tension or impact force

and on the qualities and initial tensions of the springs, so that the said opposite draw-bar half instantaneously acts on the draw and buffer gear of the neighbouring car. 60

The accompanying drawing shows in Figs. 1 and 2 the central part of the mechanism.

The draft and buffer rods 32 which are shown in the drawings only in part, are 65 attached to the shafts of the coupling heads at the ends of the car in any appropriate manner.

g, h, i, j, l are ledges, cross girders, abutments or sleeves firmly connected to the underframe. 109, 84, 106, 103, 94 are sleeves keyed on the rod 32. 50 is a sleeve, which is either mounted on the rod 32 or kept on the latter by the sleeve 94. 70

The sleeves 50 and 94 may be made in one 75 piece; 53 is a sleeve, provided with an air-outlet hole and firmly screwed on the rod 32; it causes the rods 32 to push against each other with a larger contact face in the case of heavy mutual shocks. The sleeves 80 53, 50 and 94 can be made in one piece if desired.

84 and 39 are springs abutting against the underframe; they will be efficient either simultaneously or successively according to 85 whether or not there is a clearance at either of them between the working sleeves and the spring seats.

33, 35, 38, 40, 100, 49 are seats for the springs and consists of plates; 93 is the main sleeve connecting both draw-bars and 101, 101 are connecting rods between two plates, 100 and 100, the latter being slideable on these connecting rods towards each other but are prevented from moving asunder by 95 the nuts 102. The plate 49 is displaceable relatively to plate 100.

In Fig. 1 the middle parts are symmetrically arranged whilst in Fig. 2 the spring 96 48 with its connected parts is provided only at one end of the main sleeve 93.

As to the mode of construction according to Fig. 1 upon shock from one end the spring 39 and immediately thereafter the spring 34 of the first car-half is pressed against the 105 abutments j and h; moreover, instantly at the beginning of the shock the sleeve 103 presses on spring 48 by means of plate 100, spring 48 in its turn upon main sleeve 93 by means of plate 49, finally the main sleeve 110 93 presses on spring 48 of the second car section by means of plate 49. The spring

48 presses by the aid of plate 100 against the sleeve 103 keyed on rod 32, so that also the rod 32 of the second car-half will be moved out of the car and the springs 39 and 34 of the second half of car are pressed against abutments *i*, and *g* respectively. The amount of displacement of rod 32 in the second car section depends upon the energy of shock and on the elasticity and initial tension of the springs.

Upon shocks at both car ends the springs 39 and 34 in both car sections are pressed against their abutments *j* and *h* respectively, and both springs 48 against the central main sleeve 93. Should the shock be so heavy that after being overcome the spring resistance the ends of the bars 32 abut against each other, the impact forces, inasmuch as they surpass the amount given by the spring resistance are imparted directly and centrally from one rod 32 to the other.

Upon pull at one car end the spring 39 and a little later the spring 34 of the first car section is pressed against abutments *i*, and *g* respectively; additionally in the beginning of the operation the sleeve 50 keyed on rod 32 presses by means of spring seat 49 against spring 48, the latter in turn pressing against spring seat 100. This spring seat pulls by means of the nuts 102 and the rods 101 against plate 100 of the second car section and this plate presses against spring 48 in this section of the car. The spring 48 presses by means of spring seat 49 against sleeve 50 in the second car section so as to pull the rod 32 of the latter by sleeve 50 into the car. Thereby the spring 39 of the second car section is pressed against abutment *j*, and, a little later the spring 34 against abutment *h*.

The amount of displacement of the second rod 32 depends upon the force of pull and on the qualities and initial tension of the springs.

Upon the occurrence of pull at both car ends the springs 39 and 34 in both car sections are pressed against their abutments *i* and *g* respectively and both springs 48 by the sleeves 50 and their spring seats 49 are pressed against the spring plates 100, which because of the nuts 102 and the rods 101, cannot move asunder so that the springs 48 are compressed between the plates 100 and 49. If the pull is so strong, that the sleeves 94 keyed on rods 32 after having overcome the resistance of spring abut on the thickened ends of the main sleeve 93, the tensile forces, inasmuch as they surpass the amount given by the resistance of spring, are transmitted centrally from one rod 32 to the other by the main sleeve 93.

The maximum path of a rod 32, upon pull or shock is given by the distance between the sleeves 103 or 106 respectively from the ledge 1 or other suitable abutment. It is

convenient that this path be considerably larger than half the distance that both draw-rods 32 can move to or from each other.

In the modification, Fig. 2, the spring 48, the spring seats 100 and 49 are only on one rod 32, which is slidable with respect to the connecting sleeve 93, upon shock and draft. The connecting sleeve 93 is connected to the other rod 32 by the sleeves 110 and 112 secured thereon, or otherwise, or the plate 111 that lies against the connecting sleeve may be secured to its rod 32 in another manner so that it does not move on this rod. The plate 100 is so connected to the plate 111 by the parts 101 and 102 that said plates 100 and 111 can move toward one another, while their separation is prevented by the nuts 102. The movement apart of both rods 32 is limited by the connecting member 93, by which heavy draft at both ends of the car is transmitted from one rod 32 to the other after overcoming the resistance of the springs.

Upon shock from both sides the ends of both rods 32 will abut after having overcome the resistance of springs. The play of one rod 32 upon pull is given by the distance between sleeve 112 and the neighbouring ledge 1.

The rest of the arrangement is just the same as in Fig. 1, the operation being likewise a similar one.

In the mode of construction according to Figs. 1 and 2 the springs 34, 39 lying against the underframe can be provided by any desired number of springs.

In the mode of construction according to Figs. 1 and 2 the arrangement for convenience may be so chosen, that the springs 34, 39 situated between parts of the draw and buffer gear and parts of the underframe are provided but in one half of car, if desired in a plurality of sets of springs and the draw and buffer rod 32 of the other car half remains without any springs lying against the underframe. Upon actions on this draw and buffer rod the springs 34, 39 lying against the underframe are then indirectly pressed against the respective ledges of the underframe by the aid of the moving end sleeve 93 and of the spring 48.

For reinforcing the spring mechanism in lieu of one spring 48 or besides this spring two parallel springs may be provided at the end of main sleeve 93, for example on the rods 101 in the clearance between the plates 100 and 49.

Further it may be convenient under certain circumstances to carry out the construction in such a way that first one or several of the springs lying against the underframe are under strain and only a little later the spring 48. In order to accomplish this condition it will be sufficient—upon impact force—if a little clearance is provided

in the position of rest between sleeve 103 and plate 100 or if the sleeve 50 extends a little from the main sleeve 93 when in the position of rest. In order to accomplish the said 5 condition upon pull action a small clearance between the nuts 102 and plate 100 may be provided or a similar arrangement be chosen.

What we claim is:

1. In a draft mechanism for railway vehicles of the kind extending from one car end to the other; a draw-gear comprising 10 two alined draw-bar sections, means connecting the adjacent ends of said sections while permitting limited movement toward 15 and from one another, the construction being such as to enable the said sections to abut upon shocks, one or more springs on the draw gear at the ends of said connecting means so that upon shocks the springs 20 act thereon, spring seat's in both sections between which said springs are located, means at the end of each draw-bar section and acting on the aforementioned springs, when the draw-bar section is under draft, contrivances for connecting the spring seats of 25 both sections that are spaced from the said connecting means to transmit draft from one section to the other, and springs on the draft mechanism which upon draw and 30 buffer actions will be pressed against parts of the under frame.
2. In a draft mechanism for railway vehicles of the kind extending from one car end to the other, a draw gear comprising 35 two alined draw-bar sections, means connecting said sections and permitting limited displacement of one section relatively to the other, the amount of displacement upon shocks being sufficient to enable both 40 sections to abut, means on one of said sections to prevent it from being moved

into the connecting means upon shock, one or more springs on the other section at one end of the connecting means to transmit shocks from one section to the other, a 45 seat for said springs at the end of said connecting means, and a seat for the opposite end of said springs, which seats are movable toward each other, and springs on the draw gear which upon the draw and 50 buffer actions will be pressed against parts of the under frame.

3. In a draft mechanism for railway vehicles of the kind extending from one car end to the other; a drawing-gear comprising 55 two alined draw-bar sections, means connecting said sections and permitting limited movement of the sections to and from each other, means on one of said sections to prevent it from moving into 60 said connecting means, one or more springs on the other draw-bar section at one end of said connecting means to transmit shocks from one section to the other; a seat for 65 said springs at the end of said connecting means, and a seat for the opposite end of said springs, said seats movable toward one another, means to connect the latter spring seat to the other draw-bar section to hold 70 said seat, upon draft, stationary with respect to the latter section to transmit draft from one section to the other by means of said springs, whereby upon heavy draft the movement apart of the two draw-bar sections is limited by said first means and 75 springs connecting the draft mechanism to the car frame.

In testimony that we claim the foregoing as our invention, we have signed our names.
